SHOE BOTTOM UNIT AND METHOD OF
MAKING THE SAMEWalter W. Prue, Auburn, Maine, assignor to
United Shoe Machinery Corporation, Pat-
erson, N. J., a corporation of New Jersey

Application July 20, 1933, Serial No. 681,331

22 Claims. (Cl. 36—76)

This invention relates to improved methods of making shoes and shoe bottom units and to improvements in shoes and shoe bottom units as articles of manufacture.

5 In United States Letters Patent No. 2,055,542, granted September 29, 1936, upon application of Karl Kilburn, and No. 2,065,463, granted December 22, 1936, upon application of John M. Whelton, there are disclosed and claimed cer-
10 tain improvements in shoe bottom construction and improved methods of making shoe bottom units a purpose of which is to facilitate the lasting of the upper and the laying of the outsole so as accurately to reproduce the lines of the last
15 in the shank portion of the shoe.

Among other objects the present invention is concerned with further facilitating the attainment of the above results.

With this object in view the present invention, 20 considered in one aspect, provides an improved method of making shoe bottom units which comprises assembling an unmolded insole member and a shank reinforcing piece with adhesive between the parts, said reinforcing piece having 25 been previously arched both lengthwise and crosswise to conform to the bottom contour of the shank portion of a last, and applying pressure to said parts to shape the shank portion of the insole member to conform to the lengthwise and 30 crosswise curvatures of the shank-reinforcing piece and consequently of the last bottom and to secure said parts together in a manner permanently to retain the shape imparted to the insole member. As herein illustrated, the insole mem- 35 ber is a full length insole which may be made of leather or a suitable leather substitute soling material. The illustrated reinforcing piece, which may be made of leatherboard, fiber or like material, is adapted to reinforce the heel as well 40 as the shank portion of the insole and is cut to correspond in outline to those portions of the insole. The reinforcing piece is preferably molded before assembly with the insole to conform to the bottom contour of the heel and shank 45 portions of a last and, as illustrated, the reinforcing piece is secured to the upper (i. e., the last-engaging) surface of the insole, and a metallic shank stiffener is interposed between the reinforcing piece and the insole to maintain 50 permanently the longitudinal curvature of the latter, the shank stiffener preferably being attached to the reinforcing piece before the latter is secured to the insole. The adhesive which is employed between the reinforcing piece and the 55 insole is caused to unite those parts through

pressure exerted by the hands of the workman who assembles the parts and, in order to insure that the parts shall be firmly secured together, one or more fastenings, illustrated as wire staples, may be driven through the shank portions of the 5 insole and the reinforcing piece at opposite sides of the shank stiffener. These staples hold the marginal portions of the insole and the reinforcing piece securely together, the pressure applied to the assembled parts by the staple inserting 10 instrumentalities supplementing the manually applied pressure to insure an even more effective adhesive attachment of the parts in the shank portion of the insole unit. Preferably, and as illustrated, the metal shank stiffener is formed 15 with a longitudinal rib or ridge which functions initially to produce a corresponding longitudinal ridge in the shank portion of the insole, the staples cooperating with the shank stiffener 20 permanently to retain the ridge formation of the insole so that later, after the upper has been lasted and the outsole attached, the pressure applied to the outsole in the leveling operation will produce a corresponding ridged formation in the shank portion of the outsole of the shoe. It 25 will be seen that, in accordance with the above-described method of making a reinforced shoe bottom unit, the heel and shank portions of the unit will be shaped to conform to the bottom contour of the heel and shank portions of the last before the unit is applied to the last and without placing the unit in a mold or on a form and without subjecting it to heavy molding pressure. For 30 the purpose of insuring against breaking down of the longitudinal arch of the insole unit while the shoe is being worn, provision is made, as herein illustrated, for enabling a fastener, such as a rivet, to be inserted through the outsole and through the shoe bottom unit in the forward portion of the shank of the shoe. To this end, as 35 herein shown, a fastener-receiving aperture is provided in the forward portion of the shank stiffener and a corresponding aperture registering with the former is provided in the heel and shank reinforcing member.

In the manufacture of a shoe in which the above-described reinforced insole unit is employed as herein exemplified, the unit, after being assembled and shaped as already described, is secured to the bottom of a last, an upper is pulled over and lasted to the insole, an outsole is laid, and the other usual operations are performed to complete the making of the shoe. Thereafter, the last is pulled and the rivet or other fastener is driven inwardly through the 40 45 50 55

outsole and the insole and through the apertures in the shank stiffener and reinforcing piece and the inner end of the rivet is clenched against the inner face of the reinforcing piece, thus rigidly securing all these parts together in a manner permanently to retain the longitudinal arch of the shoe bottom.

The invention further resides in improvements in shoes and in reinforced shoe bottom units resulting from the practice of the methods above outlined.

The invention will be explained with reference to the accompanying drawing, in which

Fig. 1 is a perspective view of a reinforcing piece constituting one of the elements of my improved reinforced shoe bottom unit;

Fig. 2 is a perspective view of the reinforcing piece showing a shank stiffener attached thereto;

Fig. 3 is a perspective view of a completed shoe bottom unit embodying my invention, showing the upper side of the unit;

Fig. 4 is a perspective view of the unit showing the lower or outsole-engaging side of the unit;

Fig. 5 is a longitudinal sectional view of a shoe having my improved shoe bottom unit incorporated therein; and

Fig. 6 is a sectional view taken along the line VI—VI of Fig. 3.

The improved shoe bottom or insole unit shown in the drawing comprises a full length insole 10, a reinforcing piece 12 for the heel and shank portions of the insole, and a shank stiffener 14. The insole 10 may be made of leather or any suitable leather substitute soiling material and is cut to the required shape and size in any suitable manner as, for example, by a rounding or dieing-out operation. The reinforcing member may be made of stiff leather or fibreboard and is shaped to correspond substantially to the contour of the heel and shank portions of the insole. The shank stiffener 14 is preferably made of metal and provided, as shown in Fig. 2, with a longitudinal stiffening rib or ridge 16. For use in shoes of different sizes it is, of course, necessary to cut the insoles in sizes to correspond with the sizes of the shoes. It is unnecessary, however, to provide a complete run of sizes of the reinforcing pieces on account of the relatively small change in shape in the heel and shank portions of an insole resulting from changes in size of the insole. Accordingly, it is practicable to employ a single size of reinforcing piece for a run of several sizes of insoles, it being necessary to provide only three or four sizes of reinforcing pieces for use with a lot of insoles comprising an entire run of sizes. Thus, by selecting a reinforcing piece of a size appropriate for use with an insole of a given size the reinforcing piece will correspond as closely as is necessary to the shape of the heel and shank portions of the insole.

As indicated at 18 in Fig. 2, the forward portion of the reinforcing piece 12 is beveled, thereby reducing its thickness so that it will conform readily to the abrupt break in the longitudinal curvature of the last bottom at the junction of the shank and forepart thereof and producing a feather edge which will have no tendency to form an objectionable ridge in the insole. Preferably, the lateral edges of the reinforcing piece 12 are also beveled, as best shown at 28 in Fig. 6, to facilitate smooth lasting of the shoe upper over the edges of the insole unit in the shank portion of the shoe. As shown in Fig. 6, the shank

portion of the insole 10 is cut somewhat narrower than the corresponding portion of the reinforcing piece so that the edges of that portion of the insole will have no tendency to hold the upper away from the sides of the last or to interfere with the smooth lasting above referred to. As shown, also, the shank stiffener 14 is attached by means of tacks 22 to the reinforcing piece.

The front end of the shank stiffener is located some distance rearwardly from the front end of the reinforcing piece 12 so that when the insole unit is incorporated in a shoe the front end of the shank stiffener will be spaced rearwardly from the break line of the shoe and thus the stiffener will have no tendency to dig into the outsole as the shoe is being worn.

The reinforcing piece 12, before being assembled with the insole, is molded to conform to the bottom contour of the heel and shank portions of the last for the shoe in which the insole unit is to be incorporated, the reinforcing piece, as shown, being arched both longitudinally and transversely to fit the correspondingly arched portions of the last bottom. Preferably, also, the shank stiffener 14 is provided near its front end

with an aperture 24 and a similar aperture 26 is provided in the reinforcing piece 12 in registry with the aperture 24, the registering apertures 24 and 26 being adapted to receive a fastening, such as the rivet shown at 28 in Fig. 5, for use in securing the shank portion of the insole unit to the outsole of the shoe. The reinforcing piece 12, with the shank stiffener 14 attached thereto, is secured to the insole 10 by means of suitable adhesive, such as rubber latex, and in addition by means of fastenings, such as wire staples 30, the staples, as herein shown, being employed only in the shank portion of the insole unit and being located at opposite sides of the shank stiffener.

The shank and heel portions of the illustrated insole conform to the molded contour of the reinforcing piece 12 except in the vicinity of the median line of the shank where the rib or ridge 16 of the shank stiffener forms a corresponding ridge 32 (Fig. 4) in the insole, the shank stiffener and the staples 30 cooperating to retain permanently this ridged formation in the insole so that during the manufacture of a shoe in which the reinforced insole is incorporated the pressure to which the outsole is subjected during the leveling operation will result in forming a corresponding ridge or so-called cottage-roof formation in the outsole.

In the manufacture of the above-described reinforced insole unit the reinforcing piece may be dieled out, its front and lateral edges may be beveled, a longitudinally arched shank stiffener may be assembled therewith and secured thereto, and the reinforcing piece may be molded in substantially the same manner as that customarily practiced in the manufacture of shank stiffeners for turn shoes. If desired, the rivet-receiving apertures in the reinforcing piece and in the shank stiffener may be formed therein during the dieing or blanking out of those parts, in which case the aperture in the reinforcing piece will be aligned with the aperture in the shank stiffener during the assembling of the parts and thus will serve as a means for gaging the longitudinal relation of the parts. It may be found convenient, however,

to form the aperture in the reinforcing member by punching or drilling through the aperture in the shank stiffener after the shank stiffener has been attached to the reinforcing piece.

Before the reinforcing piece 12 is assembled

with the insole 10, the shank stiffener 14 is attached to the reinforcing piece 12 by means of tacks 22.

The shank stiffener 14 is provided with an aperture 24 and a similar aperture 26 is provided in the reinforcing piece 12 in registry with the aperture 24, the registering apertures 24 and 26 being adapted to receive a fastening, such as the rivet shown at 28 in Fig. 5, for use in securing the shank portion of the insole unit to the outsole of the shoe.

The reinforcing piece 12, with the shank stiffener 14 attached thereto, is secured to the insole 10 by means of suitable adhesive, such as rubber latex, and in addition by means of fastenings, such as wire staples 30, the staples, as herein shown, being employed only in the shank portion of the insole unit and being located at opposite sides of the shank stiffener.

The shank and heel portions of the illustrated insole conform to the molded contour of the reinforcing piece 12 except in the vicinity of the median line of the shank where the rib or ridge 16 of the shank stiffener forms a corresponding ridge 32 (Fig. 4) in the insole, the shank stiffener and the staples 30 cooperating to retain permanently this ridged formation in the insole so that during the manufacture of a shoe in which the reinforced insole is incorporated the pressure to which the outsole is subjected during the leveling operation will result in forming a corresponding ridge or so-called cottage-roof formation in the outsole.

In the manufacture of the above-described reinforced insole unit the reinforcing piece may be dieled out, its front and lateral edges may be beveled, a longitudinally arched shank stiffener may be assembled therewith and secured thereto, and the reinforcing piece may be molded in substantially the same manner as that customarily practiced in the manufacture of shank stiffeners for turn shoes. If desired, the rivet-receiving apertures in the reinforcing piece and in the shank stiffener may be formed therein during the dieing or blanking out of those parts, in which case the aperture in the reinforcing piece will be aligned with the aperture in the shank stiffener during the assembling of the parts and thus will serve as a means for gaging the longitudinal relation of the parts. It may be found convenient, however,

to form the aperture in the reinforcing member by punching or drilling through the aperture in the shank stiffener after the shank stiffener has been attached to the reinforcing piece.

Before the reinforcing piece 12 is assembled

with the insole 10, the shank stiffener 14 is attached to the reinforcing piece 12 by means of tacks 22.

The shank stiffener 14 is provided with an aperture 24 and a similar aperture 26 is provided in the reinforcing piece 12 in registry with the aperture 24, the registering apertures 24 and 26 being adapted to receive a fastening, such as the rivet shown at 28 in Fig. 5, for use in securing the shank portion of the insole unit to the outsole of the shoe.

The reinforcing piece 12, with the shank stiffener 14 attached thereto, is secured to the insole 10 by means of suitable adhesive, such as rubber latex, and in addition by means of fastenings, such as wire staples 30, the staples, as herein shown, being employed only in the shank portion of the insole unit and being located at opposite sides of the shank stiffener.

The shank and heel portions of the illustrated insole conform to the molded contour of the reinforcing piece 12 except in the vicinity of the median line of the shank where the rib or ridge 16 of the shank stiffener forms a corresponding ridge 32 (Fig. 4) in the insole, the shank stiffener and the staples 30 cooperating to retain permanently this ridged formation in the insole so that during the manufacture of a shoe in which the reinforced insole is incorporated the pressure to which the outsole is subjected during the leveling operation will result in forming a corresponding ridge or so-called cottage-roof formation in the outsole.

In the manufacture of the above-described reinforced insole unit the reinforcing piece may be dieled out, its front and lateral edges may be beveled, a longitudinally arched shank stiffener may be assembled therewith and secured thereto, and the reinforcing piece may be molded in substantially the same manner as that customarily practiced in the manufacture of shank stiffeners for turn shoes. If desired, the rivet-receiving apertures in the reinforcing piece and in the shank stiffener may be formed therein during the dieing or blanking out of those parts, in which case the aperture in the reinforcing piece will be aligned with the aperture in the shank stiffener during the assembling of the parts and thus will serve as a means for gaging the longitudinal relation of the parts. It may be found convenient, however,

to form the aperture in the reinforcing member by punching or drilling through the aperture in the shank stiffener after the shank stiffener has been attached to the reinforcing piece.

Before the reinforcing piece 12 is assembled

with the insole 10, the shank stiffener 14 is attached to the reinforcing piece 12 by means of tacks 22.

The shank stiffener 14 is provided with an aperture 24 and a similar aperture 26 is provided in the reinforcing piece 12 in registry with the aperture 24, the registering apertures 24 and 26 being adapted to receive a fastening, such as the rivet shown at 28 in Fig. 5, for use in securing the shank portion of the insole unit to the outsole of the shoe.

The reinforcing piece 12, with the shank stiffener 14 attached thereto, is secured to the insole 10 by means of suitable adhesive, such as rubber latex, and in addition by means of fastenings, such as wire staples 30, the staples, as herein shown, being employed only in the shank portion of the insole unit and being located at opposite sides of the shank stiffener.

with the insole 10 a coating of adhesive, for example rubber latex, is applied to one or both of these parts. Conveniently, the reinforcing piece may be dipped in a container of latex and the 5 latex may be applied to one side of the heel and shank portion of the insole by drawing the latter across a roll which is partially submerged in latex. The reinforcing member and the insole may be readily assembled manually, the operative using 10 his fingers to align the rear and lateral edges of the parts and to press them together to cause them to adhere to each other. After the reinforcing piece and the insole have been thus assembled the staples 30 or other fastenings are 15 driven through the lateral margins of the shank portions of the assembled parts. If staples are employed they may be driven by means of a fastener-inserting machine such, for example, as that disclosed in United States Letters Patent 20 No. 1,011,592, granted December 12, 1911, upon application of W. J. Drey. In the operation of a machine of that general type not only may a row of staples be driven in a manner firmly to secure together the marginal portions of the reinforcing piece and the insole but the machine 25 operates also to clamp the work in the region where the staples are inserted with a substantial amount of pressure and this clamping pressure is effective to insure that a satisfactory bond 30 will be obtained between the adhesive-coated parts in the immediate vicinity of the clamping instrumentalities. If, as herein shown, no staples or similar fastenings are employed in the heel portions of the insole and the reinforcing piece, 35 the heel portions of those parts will be adequately secured together by the pressure of the operator's hands during the assembling and subsequent handling of the parts and by the pressure to which the parts are subjected during 40 subsequent shoemaking operations. Advantageously the staples may be driven into the outer surface of the reinforcing piece and clenched against the outsole-engaging surface of the insole since this manner of driving the staples insures against the 45 presence of any undesirable roughness in the face of the reinforcing piece which is to be directed toward the foot. The use of staples or other fastening devices, in addition to the adhesive, for securing the parts together is particularly 50 desirable in cases where a ribbed, ridged, or transversely arched shank stiffener is employed since the insertion of the staples assists in bending the insole about the shank stiffener. After being inserted the staples serve in conjunction with the 55 shank stiffener to retain the insole in its transversely bent or ridged condition.

In accordance with the above-described method a reinforced shoe bottom or insole unit may be 60 produced the heel and shank portions of which are shaped to conform to the bottom contour of the heel and shank portions of a last before being applied to the last and without placing the insole unit in a mold or upon a form and subjecting it 65 to heavy molding pressure, the only molding operation being that carried out in connection with the initial shaping of the reinforcing piece. If desired, however, this initial shaping or molding of the reinforcing piece may be dispensed with 70 and, after the reinforcing piece and the insole have been assembled and secured together, the insole unit thus produced may be molded between suitably shaped mold members in a molding machine, such, for example, as the sole molding machine disclosed in United States Letters Patent No. 75

1,003,971, granted September 26, 1911, upon application of A. A. Ball, Jr.

After the reinforcing piece has been attached to the insole and the insole has been shaped in its shank portion as above described, the resulting insole or shoe bottom unit is laid upon the bottom of a last and held in place thereon by tacks driven into the last bottom in the usual way, the unit fitting the last as a result of the shaping operations already described and in spite of the fact that the insole has not been subjected to any actual molding operations such as have heretofore been used to impart the desired shape to the insole.

In the making of a shoe upon the last fitted with my improved reinforced insole unit, an upper is pulled over the last and secured in lasted relation to the insole, an outsole is laid and secured to the shoe bottom, and a heel is attached, all in accordance with any well-known or suitable practice. Such a shoe is illustrated in Fig. 5, the shoe comprising, in addition to the improved insole unit, an upper 34, an outsole 36 attached by cement to the shoe bottom, and a heel 38, secured in place by heel-attaching nails 40. It is to be noted that a shoe embodying the herein-described reinforced insole or bottom unit is particularly adapted to have its outsole secured by means of cement, inasmuch as there is no metal at the lower side of the insole to interfere with the bond between the outsole and the shoe bottom in the shank portion of the latter, though obviously the outsole may be attached by stitching if preferred.

In order to provide for more firmly and adequately stiffening the shank portion of the shoe and overcoming any tendency of the longitudinal arch of the shoe to break down under the weight of the wearer, it is preferred to secure the reinforcing piece, the shank stiffener, and the inner and outer soles together at the forward portion of the shank of the shoe by means of a strong fastening, such as the rivet 28 already referred to. In practice it has been found unnecessary to provide rivet-receiving apertures in the insole 10 or in the outsole prior to the driving of the rivet. The rivet may be driven by the use, for example, of a rivet-driving device of the type wherein a positioning pin associated with one member of a rivet-setting couple is adapted to enter the apertures in the shank stiffener and reinforcing piece and to position those parts with the apertures therein in line with a rivet held in position to be driven by the other member of the rivet-setting couple. A rivet-driving device of this general nature is disclosed in United States Letters Patent No. 1,829,787, granted November 3, 1931, upon application of J. F. Crowley. In the use of a rivet-driving device of this nature the rivet will be caused to force its way through the previously unperforated outer and inner soles of the shoe and thereafter to pass through the aligned apertures in the shank stiffener and reinforcing piece. Finally, the rivet will be set by having its inner end clenched against the inner surface of the reinforcing member. If desired, the use of a rivet-driving device such as that above referred to may be dispensed with by the expedient of inserting a drill, punch or other hole-forming tool in the apertures 24 and 26 in the shank stiffener and reinforcing piece, respectively, and operating the tool to form holes through the insole and outsole of the shoe in line with the apertures in the shank stiffener and reinforcing piece, after

which a rivet may be passed through the holes in the various shoe bottom parts mentioned and set without the use of the special rivet-driving mechanism referred to. The use of the rivet or other fastener, as described, insures that the members employed for reinforcing and stiffening the shank portion of the shoe bottom will be firmly secured together in such a manner as to maintain the longitudinal arch of the shoe bottom throughout the life of the shoe.

In cases where an insole or bottom unit constructed in accordance with my invention comprises an insole member made of a leather substitute it is to be noted that the location of the reinforcing piece at the upper or last-engaging side of the insole member is particularly advantageous inasmuch as the strength and toughness of the leatherboard, fiber or like material of which the reinforcing piece is composed affords a more secure anchorage for the rivet 28 and for the heel-attaching nails 40 than would be afforded by the weaker insole material, it being practically impossible for the heads of the heel-attaching nails or the clenched-over inner end of the rivet 28 to be pulled outwardly through the reinforcing piece 12, whereas experience has shown that the materials commonly employed as substitutes for leather will not satisfactorily resist the strains to which the heel-attaching nails are subjected in the wearing of a shoe.

Having described my invention, what I claim as new and desire to secure by Letters Patent of the United States is:

1. That improvement in methods of making reinforced shoe bottom units which consists in assembling an unmolded insole member and a shank-reinforcing piece with adhesive between said parts, said reinforcing piece having been previously arched both lengthwise and crosswise to conform to the bottom contour of the shank portion of a last, and applying pressure to said parts to shape the shank portion of the insole member to conform to the lengthwise and crosswise curvatures of the shank-reinforcing piece and consequently of the last bottom and to secure said parts together in a manner permanently to retain the shape imparted to the insole member.

2. That improvement in methods of making reinforced shoe bottom units which consists in assembling a heel and shank reinforcing piece and an unmolded insole with adhesive between said parts, said reinforcing piece being molded both longitudinally and transversely in conformance with the longitudinal and transverse curvatures of the bottom of the heel and shank portions of a last and arranged to overlie and substantially to cover the upper side of the heel and shank portions of the insole, and pressing said parts together, thereby causing them to become united by means of the adhesive and shaping the heel and shank portions of the insole to conform to the reinforcing piece.

3. That improvement in methods of making reinforced shoe bottom units which consists in assembling a reinforcing piece previously molded to conform to the bottom contour of the shank portion of a last and an unmolded insole with adhesive between said parts, and inserting fastenings through one of said parts into the other, thereby causing the adhesive and the fastenings to secure said parts firmly together and conforming the shank portion of the insole to the reinforcing piece.

4. That improvement in methods of making reinforced shoe bottom units which consists in as-

sembling a heel and shank-reinforcing piece and an unmolded insole with adhesive between said parts, the reinforcing piece having been previously molded to conform to the bottom contour of the heel and shank portions of a last and having a shank stiffener attached to its insole-engaging side, and inserting fastenings through the lateral marginal portion of one of said parts into the other, thereby causing the adhesive and the fastenings to secure said parts firmly together and conforming the shank portion of the insole to the reinforcing piece.

5. That improvement in methods of making reinforced shoe bottom units which consists in applying adhesive to the heel and shank portions of a flat insole and to a heel and shank-reinforcing piece previously molded to conform to the bottom contour of the heel and shank portions of a last, laying the said reinforcing piece in correct position upon the insole, and applying pressure to said parts to secure them together and to conform the heel and shank portions of the insole to the reinforcing piece.

6. That improvement in methods of making reinforced shoe bottom units which consists in applying adhesive to the heel and shank portions of a flat insole and to a molded heel and shank-reinforcing piece having a longitudinally arched shank stiffener secured to its insole-engaging side and inserting fastenings into the shank portions of the insole and the reinforcing member at opposite sides of the shank stiffener, thereby causing said parts to be firmly secured together by said fastenings and by the adhesive, and conforming the shank portion of the insole to the reinforcing piece.

7. That improvement in methods of making reinforced shoe bottom units which consists in assembling a heel and shank-reinforcing piece and an unmolded insole with adhesive between said parts, the reinforcing piece having been previously shaped to conform to the bottom contour of the heel and shank portions of a last and having attached to its insole-engaging side a longitudinally arched shank stiffener having a longitudinal ridge at the insole-engaging side of the reinforcing piece, and inserting fastenings in the lateral margins of the shank portions of the reinforcing member and the insole, thereby causing the adhesive and the fastenings to secure said parts firmly together and conforming the shank portion of the insole to the longitudinal curvature of the reinforcing piece and forming in the shank portion of the insole a longitudinal ridge corresponding to that of the shank stiffener.

8. That improvement in methods of making reinforced shoe bottom units which consists in assembling a heel and shank reinforcing piece and an unmolded insole with adhesive between said parts, the reinforcing piece having attached to its insole-engaging side a longitudinally and transversely arched shank stiffener, pressing the insole and the reinforcing piece together, thereby causing them to become united by means of the adhesive and conforming the shank portion of the insole to the longitudinal curvature of the shank stiffener, and inserting fastenings in the lateral margins of the insole and the reinforcing piece, thereby conforming the shank portion of the insole to the transverse curvature of said shank stiffener.

9. That improvement in methods of making shoes which consists in assembling an unmolded insole and a heel and shank-reinforcing piece with adhesive between said parts, the reinforcing

piece having been previously molded to conform to the longitudinal and transverse curvatures of the bottom of the heel and shank portions of a last and having a shank stiffener attached to its 5 insole-engaging side, applying pressure to said parts, thereby securing the insole to the reinforcing piece and shaping the shank portion of the insole to conform to the shank portion of the reinforcing piece, applying the insole unit thus produced to the bottom of a last, lasting an upper 10 to the insole, and attaching an outsole and a heel to the shoe.

10. That improvement in methods of making shoes which consists in applying to the bottom of 15 a last a shoe bottom unit comprising an insole member, a heel and shank-reinforcing piece having a fastener-receiving aperture therein and a shank stiffener having a fastener-receiving aperture registering with the aperture in said reinforcing piece, lasting an upper to said shoe bottom unit, attaching an outsole and a heel to the shoe, pulling the last, and inserting a fastener through 20 the outsole and the insole member and through the registering apertures in the shank stiffener 25 and reinforcing piece to secure together the outsole, insole, shank stiffener and reinforcing piece.

11. That improvement in methods of making shoes which consists in securing to the heel and shank portions of a flat insole a longitudinally 30 and transversely curved reinforcing piece having a rivet-receiving aperture therein, and a shank stiffener having a rivet-receiving aperture registering with the aperture in the reinforcing piece and thereby imparting longitudinal and trans- 35 verse curvatures to said insole and producing a shoe bottom unit, applying the shoe bottom unit thus produced to the bottom of a last, lasting an upper to said unit, attaching an outsole and a heel to the shoe, pulling the last, driving a rivet 40 inwardly through the outsole and through the registering apertures in the shank stiffener and reinforcing member, and clenching the inner end of the rivet against the inner surface of the reinforcing member rigidly to secure together the 45 outsole, the insole, the shank stiffener and the reinforcing member.

12. A reinforced shoe bottom unit comprising an innersole member having a longitudinally arched shank portion, a reinforcing piece for the 50 shank portion of the innersole member secured to the latter, and a shank stiffener interposed between the reinforcing piece and the innersole member and directly secured to the reinforcing piece, the shank stiffener having an open rivet- 55 receiving aperture therein and the reinforcing member having an open rivet-receiving aperture therein registering with the aperture in the shank stiffener.

13. A reinforced shoe bottom unit comprising 60 an innersole having a longitudinally and transversely arched shank portion, a reinforcing member for the heel and shank portions of the innersole, a ribbed shank stiffener interposed between the reinforcing member and the innersole and 65 imparting a corresponding ribbed contour to said innersole, and a series of staples securing together the marginal portions of the innersole and the reinforcing member at the shank portion of the innersole, the staples being set inwardly from the 70 edge of said parts so as to preserve the ribbed contour of the innersole.

14. A reinforced shoe bottom unit comprising 75 an innersole, a reinforcing piece secured to the heel and shank portions of the innersole, each of

versely and the innersole being arched transversely to a greater extent than the reinforcing piece, a longitudinally arched shank stiffener interposed between the innersole and the reinforcing piece, and fastenings securing together the marginal portions of the innersole and the reinforcing piece along the opposite edges of the shank stiffener and cooperating with the shank stiffener to retain the transverse arch of the innersole.

15. A reinforced shoe bottom unit comprising a longitudinally and transversely arched heel and shank reinforcing piece, a shank stiffener secured to the reinforcing piece, and an insole secured to the reinforcing piece at the side of the latter to which the shank stiffener is secured, the insole being transversely arched to a substantially greater extent than said reinforcing piece.

16. A reinforced shoe bottom unit comprising an innersole member, a heel and shank reinforcing piece secured by adhesive to said innersole member, a ribbed shank stiffener interposed between said parts, said innersole member conforming to the ribbed contour of said shank stiffener, and fastening devices located at opposite sides of and in close proximity to said shank stiffener, said devices securing the lateral marginal portions of the innersole member and the reinforcing piece together so as to preserve the ribbed contour of the latter.

17. A reinforced shoe bottom unit comprising an innersole, a heel and shank-reinforcing piece secured to the innersole, and a shank stiffener interposed between said parts, said stiffener having a longitudinal ridge imparting a correspond- 35 ing ridged formation to the innersole.

18. A reinforced shoe bottom unit comprising an innersole having a longitudinally arched shank portion, a longitudinally arched reinforcing piece for the heel and shank portions of the innersole, and a longitudinally arched shank stiffener interposed between said parts, said stiffener having a longitudinal ridge at its innersole-engaging side and said innersole having a longitudinal ridge supported by the ridge of the shank stiffener.

19. A reinforced shoe bottom unit comprising an innersole, a heel and shank-reinforcing piece completely covering the heel and a substantial portion of the shank portion of the innersole, a shank stiffener interposed between said parts and imparting a ridged formation to said innersole, and rows of staples securing together the lateral marginal portions of the innersole and the reinforcing piece, said staples being spaced substantial distances inwardly from the lateral edges of the reinforcing piece to preserve the ridged formation of the innersole.

20. A reinforced shoe bottom unit comprising an innersole, a heel and shank-reinforcing piece secured by adhesive to the innersole, and a ribbed shank stiffener interposed between said parts and imparting a corresponding ribbed contour to said innersole, and rows of staples spaced substantial distances from the lateral edges of the reinforcing piece securing the marginal portions of the innersole and the reinforcing piece together along opposite edges of the shank stiffener to maintain permanently the ribbed contour of said innersole.

21. A shoe comprising an innersole, a reinforcing member for the heel and shank portions of the innersole adhesively secured to the innersole at the inner or foot-engaging side of the latter, a shank stiffener interposed between the reinforcing member and the innersole, an upper having its margins lasted over the innersole, an out-

ersole adhesively secured to the overlasted upper margins, and a rivet extending through the reinforcing member, the shank stiffener, the innersole, and the outersole in the shank portion of the shoe.

22. A shoe comprising an innersole, a reinforcing member for the heel and shank portions of the innersole adhesively secured to the innersole at the inner or foot-engaging side of the latter, a shank stiffener interposed between the reinforcing member and the innersole and se-

cured to the reinforcing member, an upper having its margins lasteted over the innersole, an outersole adhesively secured to the overlasted upper margins, the shank portions of the reinforcing member, the innersole and the outersole being transversely concave at the sides directed toward the inside of the shoe, and a rivet extending through the reinforcing member, the shank stiffener, the innersole, and the outersole in the shank portion of the shoe.

CERTIFICATE OF CORRECTION.

Patent No. 2,073,025.

March 9, 1937.

WALTER W. PRUE.

It is hereby certified that error appears in the printed specification of the above numbered patent requiring correction as follows: Page 5, second column, line 49, claim 19, after the article "a" insert ribbed; and that the said Letters Patent should be read with this correction therein that the same may conform to the record of the case in the Patent Office.

Signed and sealed this 27th day of April, A. D. 1937.

(Seal)

Leslie Frazer
Acting Commissioner of Patents.

DISCLAIMER

2,073,025.—Walter W. Prue, Auburn, Maine. SHOE BOTTOM UNIT AND METHOD OF MAKING THE SAME. Patent dated March 9, 1937. Disclaimer filed February 17, 1938, by the assignee, United Shoe Machinery Corporation.

Hereby enters this disclaimer to claims 1, 2, 5, and 9 of said Letters Patent.

[Official Gazette March 15, 1938.]

ersole adhesively secured to the overlasted upper margins, and a rivet extending through the reinforcing member, the shank stiffener, the innersole, and the outersole in the shank portion of the shoe.

22. A shoe comprising an innersole, a reinforcing member for the heel and shank portions of the innersole adhesively secured to the innersole at the inner or foot-engaging side of the latter, a shank stiffener interposed between the reinforcing member and the innersole and se-

cured to the reinforcing member, an upper having its margins lasteted over the innersole, an outersole adhesively secured to the overlasted upper margins, the shank portions of the reinforcing member, the innersole and the outersole being transversely concave at the sides directed toward the inside of the shoe, and a rivet extending through the reinforcing member, the shank stiffener, the innersole, and the outersole in the shank portion of the shoe.
